UNITED STATES PATENT OFFICE.

AUGUST THEODOR FRIEDRICH NEHLS, OF SÜDENDE, GERMANY.

PNEUMATIC HAND-HAMMER.

SPECIFICATION forming part of Letters Patent No. 755,381, dated March 22, 1904.

Application filed April 23, 1902. Serial No. 104,263. (No model.)

To all whom it may concern:

Be it known that I, AUGUST THEODOR FRIEDRICH NEHLS, a subject of the King of Prussia, German Emperor, residing at Südende, near Berlin, in the Kingdom of Prussia, Germany, have invented certain new and useful Improvements in Pneumatic Hand-Hammers, of which the following is a specification, such as will enable others skilled in the art to which it applies to make and use the same.

The object of my invention is to provide a pneumatic hand-hammer of an extremely simple and cheap form of construction, consisting of but few parts and not liable to accidental disarrangement or accident, in which the moving portions of the valve are plungers actuated in one direction by the piston-plunger and in the other by the compressed air.

To such ends my invention consists, in substance, of a casing having a cylindrical hollow, a plunger-piston reciprocating in the casing, a reciprocating tool-stock passing through one end of the casing adapted to be forced outward by the impact therewith of the plunger-piston, a hollow valve-piston adapted to have a limited reciprocative movement located at either end of the cylinder adapted to be reciprocated toward the end of the cylinder by the impact therewith of the piston-plunger and in the other direction by the air-pressure when the piston-plunger has reached the other end of the cylinder, an annular air-groove formed on the periphery of each of the valve-pistons, a plurality of passages or ports formed in and through the peripheral wall of the pistons, an end plate closing either end of the casing, a hollow handle-piece adapted to be connected with a suitable air-pressure-supply hose or pipe, an inlet or throttle valve, means for actuating the throttle-valve, and air inlet and outlet passages formed in the walls of the casing, by which upon reciprocating of the valves first one side and then the other are alternately brought into communication with the air-pressure supply and with the atmosphere, although it is not to be understood that the device is limited to a device comprising at once all the devices and parts or the particular construction, combination, and arrangement of parts mentioned, as my inven-

tion consists in the particular arrangement of certain devices and parts and the particular construction and arrangement of certain devices and parts, all as hereinafter more particularly set forth in the description and pointed out in the claims. 55

My said invention is fully shown and described in the following specification, of which the accompanying drawings form a part, wherein similar letters of reference designate like or equivalent parts wherever found throughout the several views, and in which—

Figure 1 is a side view of my improved form of pneumatic hand-hammer in central longitudinal section on the line 2 2 of Fig. 5, the plunger-piston being shown in the center and moving toward the right in the position assumed by it when about to strike the working blow. Fig. 2 is a similar view thereof, taken in section on the line 3 3; and Fig. 3, a similar view taken in section on the line 4 4 of such Fig. 4. Fig. 4 is an end view of Fig. 1 looking toward the left, taken on the line 5 5 of Fig. 1, the handle-cap portion being wholly removed; and Fig. 5 is a like view taken in cross-section on the line 6 6 of such Fig. 1. Figs. 6 and 7 are views similar to Figs. 1 and 2, respectively, showing the position of the piston-plunger and valve-pistons at the moment when the plunger-piston is about to start upon its reverse reciprocative movement immediately after having struck its working blow. 70 75 80

Referring to the drawings, the reference-letter A designates a cylindrical casing, to one end of which is secured the handle-cap B and to the other the nose-cap C, through which reciprocates the shaft *x* of the reciprocating tool, a flanged bushing *i*, of suitable antifriction metal, being interposed between the stem of the tool *x* and the nose-cap, as shown, upon the inner end of which reciprocates back and forth the outer piston-valve *g*, a similar piston-valve *e* being located in the other end of the cylinder and the travel of each being limited by the length of the recess *g* or *n*, which is in each case of slightly-larger diameter than the cylinder-bore, a plate *i'* performing the function for the valve *e* performed for the valve *g* by the flange of the bushing *i*, such plate *i'* being 90 95 100

provided on the outer face with a groove *s* in free communication at one end with a passage *t* and at the other with the valve-chamber at the rear of the valve *e*, as shown in Figs. 3 and 4, and also with perforations in registry with the inlet-passage *b* and the exhaust-passage *h*, as shown in Figs. 1 and 6, while the flange of the bushing *i* is provided with a groove *m* and passage *w*, similar to the like groove and 10 passage *s* and *t*.

The piston-valve *e* is provided with a plurality of holes *c*, formed in and through the peripheral wall thereof, so as to communicate with the central cavity thereof, which is of 15 such size as to receive the end of the plunger-piston *f*, and the like valve *g* is provided with a similar central cavity and similar holes *d*, and upon the base of each of such piston-valves is formed an annular groove, (designated in 20 the case of the valve *e* by *u* and of *g* by *n*.) The plate or flange *i* of the bushing of the nose-piece upon the central hollow spindle of which the valve *g* reciprocates is provided with a groove and two perforations, as shown in Figs. 25 2 and 7, by which the rear face of the valve *g* is at all times in free communication with the passage *h*, formed in the wall of the casing, the other end of which passage *h* is provided with a port opened and closed by the reciprocation 30 of the valve *e*, a like passage *o* on the other side of the casing being in communication with a passage *p*, similar to the passage *l*, the port of which passage *o* is opened and closed by the reciprocation of the valve-pis- 35 ton *g*.

Formed in the wall of the casing is an air-entrance passage *b*, provided with a port at either end adapted to be opened and closed by the reciprocation of the piston-valve at that 40 end, entrance being had by way of the peripheral perforations in the valve-piston, such passage *b* being in communication with the passage *a* in the hollow handle, to the end of which is secured the air-pressure-supply hose, 45 (not shown,) in which passage *a* is located the valve *v*, manipulated by the pressure of the operator's hand upon the valve-lever in the well-known manner, and formed in the wall of the casing on the opposite side and in free 50 communication with the atmosphere is the exhaust air-passage *h*, provided at either end with two ports *h'* and *v'*, the port *h'* being adapted to be brought into and out of communication with the central portion of the 55 cylinder by way of the perforations *c* or *d*, as the case may be, upon the reciprocation of the valve and the port *v'* in like manner being by such reciprocation brought into and out of communication in the one case with the 60 peripheral groove *u* of the valve-piston *e* and in the other with the like groove *n* of the valve-piston *g*, which grooves when the valves are in such position as to bring them into registry with the port are in the case of the valve 65 *e* in registry with the passage *t* in communica-

cation with the passage *s* and in the case of the other valve with the passage *w* in communication with the passage *m* in the end plate.

The operation of the device is as follows: The plunger-piston *f* being at the handle end 70 of the cylinder, if now the valve *v* be opened by pressure exerted upon the lever thereof the compressed air will pass to the cylinder by way of the passages *a* and *b* and holes *c* in the peripheral wall of the valve, and such 75 pressure will force the piston-plunger *f* to the nose end of the cylinder in the direction of the arrow marked on such plunger in Figs. 1, 2, and 3, the exhaust-air in front of such piston-plunger *f* escaping freely into the atmosphere by way of the perforations *d* of the valve *g* and exhaust-passage *h*, and during 80 this movement the groove *u* is in registry with the port leading to such passage *h* and with the passages *t* and *s*, as shown in Fig. 3. 85 At the same instant that the plunger *f* delivers its working blow upon the inner end of the tool-shank *x* it also strikes against the valve-piston *g* and forces the same back against the nose-piece of the casing into the position 90 shown in Figs. 6 and 7, the blow upon the valve-piston being cushioned by the air confined between the same and the plate or flange of the bushing *i* during the first portion of 95 this movement, such air being released during the last portion of such movement by reason of the bringing of the registry of the port to the passage *h* with the groove *n* of such valve. At the same instant the air-entrance passage *b* is by the same movement of the valve *g* brought 100 into communication with the cylinder by way of the port and perforations *d* of such valve and such cylinder at the same time, by way of some of such perforations *d*, brought into communication with the passage *p* in communication 105 with the rear or outer face of the valve-piston *e* by way of the channel or passage *p*, which is thus by the pressure of the air forced forward into the position shown in Figs. 6 and 7, so as to close the air-inlet port of the passage *b* and open the exhaust-port *u'* at the handle end, as shown in Fig. 6, and to at the 110 same time close the port of the passage *h*, leading to the passage *e*, passages *o* and *p* of reversed position performing similar functions 115 for the other valve on the forward movement.

The handle *B* and nose-piece *C* are usually 120 removably secured upon the ends of the cylinder *A* by means of set-screws *y* and *y'*, and by having cylinders *A* of different lengths one tool may be used for many different purposes.

Having now particularly described my said invention, what I claim, and desire to secure by Letters Patent, is—

1. In a pneumatic hammer a removable handle-piece, a removable nose-piece, means for detachably securing same to cylinders of different lengths, a plunger-piston, and a removable valve-piston at either end of the cylinder removable therefrom when the end pieces are 125 130

removed actuated in one direction by the air-pressure and in the other by the plunger-piston, substantially as shown and described.

2. In a pneumatic hammer, a cylinder, a plurality of air-passages formed longitudinally of the cylinder in the wall thereof, a valve-piston located in the cylinder at either end capable of a limited reciprocative movement therein adapted to open and close the ports of the air-passages so as to bring both sides of such valve-pistons alternately into communication with the air-pressure passage and the exhaust-passage, and a plunger-piston reciprocated in the cylinder by the air-pressure adapted to force the valve-pistons to the end of the cylinder upon impact therewith, substantially as shown and described.

3. In a pneumatic hammer, a cylinder, a plurality of air-passages formed longitudinally of the cylinder in the wall thereof, a valve-piston located in the cylinder at either end capable of a limited reciprocative movement therein adapted to open and close the ports of the air-passages so as to bring both sides of such valve-pistons alternately into communication with the air-pressure passage and the exhaust-passage, a plunger-piston reciprocated in the cylinder by the air-pressure adapted to force the valve-pistons to the end of the cylinder upon impact therewith, and means for causing an air-cushion to be formed behind the valve-piston to receive the first impacting force of the plunger-piston and for releasing the air so compressed behind such valve-piston during the latter portion of the outward move of such piston.

4. In a pneumatic hammer, a cylinder, a plunger-piston, an enlarged recess formed in each end of the cylinder, a valve-piston reciprocating in each of such recesses having an inwardly-faced central recess provided with perforations in the peripheral wall and with an annular groove upon the periphery of the base, an air-entrance passage provided with an air-port at either end extending longitudinally of the casing, a like air-exhaust passage at either end with two ports one adapted to be put into and out of registry the one with the perforations and the other with the peripheral groove of the adjacent valve, such exhaust-passage being in free communication with the atmosphere and extending longitudinally of the casing, a valve-actuating air-passage in free communication at one end with the chamber between the outer face of the valve and the cylinder end and provided at the other with a port adapted to be brought into and out of communication with the cylinder upon the reciprocation of the valve adjacent to the port, a similar passage reversely located so as to perform a like function for the other valve, and an exhaust air-passage for each of the valve-pistons in communication at one end with the chamber between the outer face of the valve-piston and the casing end

and provided at the other with a port adapted to be brought into and out of communication with the peripheral groove of the valve-piston as the same is reciprocated, substantially as shown and described.

5. In a pneumatic hammer, a cylinder, a plunger-piston, an enlarged recess formed in each end of the cylinder, a valve-piston reciprocating in each of such recesses having an inwardly-faced central recess provided with perforations in the peripheral wall and with an annular groove upon the periphery of the base, an air-entrance passage provided with an air-port at either end extending longitudinally of the casing, a like air-exhaust passage provided at either end with two ports one adapted to be put into and out of registry the one with the perforations and the other with the peripheral groove of the adjacent valve, such exhaust-passage being in free communication with the atmosphere and extending longitudinally of the casing, a valve-actuating air-passage in free communication at one end with the chamber between the outer face of the valve and the cylinder end and provided at the other with a port adapted to be brought into and out of communication with the cylinder upon the reciprocation of the valve adjacent to the port, a similar passage reversely located so as to perform a like function for the other valve, and an exhaust air-passage for each of the valve-pistons in communication at one end with the chamber between the outer face of the valve-piston and the cylinder end and provided at the other with a port adapted to be in communication with the peripheral groove of the valve-piston only during the latter portion of the outward movement of such piston, substantially as shown and described.

6. In a pneumatic hammer, a cylinder, a plunger-piston, an enlarged recess formed in each end of the cylinder, a valve-piston reciprocating in each of such recesses having an inwardly-faced central recess provided with perforations in the peripheral wall and with an annular groove upon the periphery of the base, an air-entrance passage provided with an air-port at either end extending longitudinally of the casing, a like air-exhaust passage provided at either end with two ports one adapted to be put into and out of registry the one with the perforations and the other with the peripheral groove of the adjacent valve, such exhaust-passage being in free communication with the atmosphere and extending longitudinally of the casing, a valve-actuating air-passage in free communication at one end with the chamber between the outer face of the valve and the cylinder end and provided at the other with a port adapted to be brought into and out of communication with the cylinder upon the reciprocation of the valve adjacent to the port, a similar passage reversely located so as to perform a like function for the other valve,

and an exhaust air-passage for each of the valve-pistons in communication at one end with the chamber between the outer face of the valve-piston and the cylinder end and provided at the other with a port adapted to be in communication with the peripheral groove of the valve-piston only during the latter portion of the outward movement of such piston, such groove at the same time in

communication with the port of the air-exhaust passage, substantially as shown and described.

In witness whereof I have hereunto set my hand in presence of two witnesses.

AUGUST THEODOR FRIEDRICH NEHLS.
